WELLHEAD

Granville A. Humason, Houston, Tex., assignor
of one-half to E. E. Townes, Harris County,
Tex.

Application October 1, 1945, Serial No. 619,500

4 Claims. (Cl. 255—19)

1

This invention relates to a well head.

An object of the invention is to provide a novel type of well head whereby the conventional type of rotary swivel and hose may be dispensed with in carrying on the drilling operations and the drilling fluid delivered through the stationary well head into the drill stem.

Another object of the invention is to provide, in a well head, a safety sleeve depending from the head with a seal between it and the drill stem and which may rotate with the stem and independently of the head and for a purpose to be hereinafter stated.

It is a further object of the invention to provide a combination braden head and tubing head with a novel type of packing assembly around the grief pipe of the drill stem which is mounted to rotate with the drill stem, with sealing means between the safety sleeve and braden head and with a seal between the drill stem and safety sleeve whereby drilling operations may be carried on while the well is under pressure, and the separate conventional blow out preventer dispensed with.

It is a further object of the invention to provide in a well head a packing assembly between the grief pipe and tubing head which is mounted to rotate with the drill stem but which may be readily removed when it is desired to add additional sections to the drill stem as drilling progresses, or when it is desired to break up the drill stem and remove it, and the drill, from the well.

The invention also embodies novel means for connecting the tubular sections of which the well head is composed.

With the above and other objects in view the invention has particular relation to certain novel features of construction, operation and arrangement of parts, an example of which is given in this specification and illustrated in the accompanying drawings, wherein—

Figure 1 is a side view of the head, shown partly in section, connected to the upper end of the well casing and showing the sleeve and drill stem installed.

Figure 2 is a side view, partly in section, of the lower end of the drilling apparatus in connection with which the head is employed.

Figure 3 is a side view of the complete drilling equipment embodying the type of head herein described.

Figure 4 is a side view, partly in section, taken on the line 4—4 of Figure 3; and

2

Figure 5 is a cross-sectional view taken on the line 5—5 of Figure 4.

Referring now more particularly to the drawings wherein like numerals of reference designate similar parts in each of the figures, the numeral 1 designates the braden head which is connected to the upper end of the well casing 2. The braden head may have one, or more, out flow lines, as 3, leading to the slush pit 4.

Mounted on the braden head there is a tubing head which, in the present illustration, is shown as composed of upper and lower tubular sections 5 and 6, the section 5 having an inside downwardly tapering annular seat 7.

The upper end of the braden head has an external, annular, flange 8 and the lower end of the tubing head has a similar external, annular, flange 9. The lower and upper sides of these flanges are formed with the annular, outwardly converging faces 10 and 11, respectively, and surrounding these flanges there is a housing 12 which is preferably formed of two sections which are bolted together, as shown in Figure 3. This housing has an internal groove 13 whose sides are inwardly flared and fit closely against the faces 10 and 11 so that when the housing 12 is clamped around the flanges it will draw them closely together. The upper end of the braden head has an annular groove 13 and the lower end of the tubing head has an annular rib 14 which fits into said groove to form a fluid tight seal when the flanges are drawn together.

The upper end of the lower section 6 of the tubing head has an external, annular flange 15 and the lower end of the upper section 5 of the tubing head has an external, annular flange 16. The lower and upper sides of these flanges have the annular, outwardly converging faces 17 and 18 and fitted around said flanges there is a housing 19 similar to the housing 12 and formed of sections which are bolted together, as shown in Figure 3. The housing 19 has an inside groove which flares inwardly and whose sides fit closely against the faces 17 and 18 so that when the housing 19 is clamped around said flanges they will be drawn tightly together.

The upper end of the lower section 6 has an annular groove 20 and the lower end of the upper section 5 has an annular rib 21 which fits in said groove to form a fluid tight seal between said sections.

Mounted in the upper end of the upper section 5 of the tubing head there is a rotatable packing assembly comprising the lower wear ring 55 22 which is seated on the seat 7 and the upper

gland 23 with the expandable resilient seal ring 24 between them and secured to them. This seal ring may be made hollow and fluid under pressure may be introduced into it, to expand it, through the pressure line 25 leading from a suitable source of pressure and equipped with a two way valve 26 which may be turned to one position to admit pressure fluid into the seal ring and to another position to relieve said fluid pressure through the relief line 27. The upper section 5 of the tubing head has an inside upwardly facing shoulder 28 to support the anti-friction rollers 29 which may be lubricated through the duct 30 which is equipped with a fitting 30a for the connection of a grease gun thereto. The gland 23 has an external downwardly facing shoulder 30 and between said shoulder 30 and the anti-friction rollers 29 there is a ring 31 which surrounds the gland 23 and supports it on said rollers. This ring has an external annular groove 32 and threaded through the wall of the section 5 there are the retainer screws 33 whose inner ends project into the groove 32 so that the ring 31 may be permitted to turn with the gland 23 on said rollers or may be permitted to rotate independently of the gland.

Around the upper end of the gland there is a packing assembly 34 which fits closely within the upper section 5 of the tubing head. Beneath the packing assembly 34 the gland has an external annular groove 35 and opposite said groove the head section 5 is provided with cylinders 36, 36 having the ends caps 37, 37 thereon and within the cylinders there are the gland retainers 38, 38 which work through aligned bearings in the head section 5 and whose inner ends project into the groove 35. The rotatable packing assembly is thus retained in the tubing head but permitted to rotate. Between the retainers 38 and the caps 37 are coil springs, as 39, which hold the retainers inwardly in active position. Attached to the retainers 38 and extending outwardly through the caps 37 are the rods 40 whose outer ends are formed with grip members 41. The retainers may thus be withdrawn from the groove 35 when it is desired to remove the packing assembly from the tubing head. The packing assembly has a polygonal, axial passageway therethrough to receive the correspondingly shaped grief joint 42 of the drill stem 43 and through which said drill stem may be rotated by the rotary drilling machine 44 of any conventional construction and shown in Figure 3. As drilling progresses the rotatable packing assembly above described will rotate with the drill stem and sufficient pressure may be applied within the seal ring 24 to prevent the escape of drilling fluid or of normal well pressure.

Rotatably mounted in the head assembly there is a hanger 45 and connected to this hanger and depending therefrom there is a safety sleeve 46 which extends down into the well and is of substantially the same length as the grief joint 42. The hanger includes a seal ring, as 47, which forms a seal between the upper end of the safety sleeve and the braden head 1.

The lower end of the grief joint 42 is connected to the upper end of the drill stem proper and as the well is deepened the grief joint is, from time to time, broken out and additional sections added to the upper end of the drill stem. In the present illustration the grief joint includes also a tubular valve casing 48 having side inlet openings 49 and above them there is a downwardly opening spring seated valve 50 which

5 closes the passageway through said grief joint. While drilling the drilling fluid from the slush pit is forced by the slush pump 51 through the inflow line 52 into the head assembly beneath the rotatable packing assembly above described and this drilling fluid enters the drill stem 43 through the inlet ports 49, the valve 50 preventing its passage upwardly through the grief joint and the rotatable packing assembly preventing 10 its passage upwardly around the grief joint 42. The drilling fluid is thus forced down through the drill stem and through the fluid passageways in the drill 53, or 53a, and returns back up through the well casing 2 and back to the slush pit through the out flow line 3.

15 In case high pressure is encountered the drill stem sections added to the upper end of the stem from time to time, as hereabove explained, may be equipped with sealing assemblies suitably secured thereto, as shown in Figure 1, and comprising upper and lower wear rings 54, 55 with seal rings, as 56, between them, said assemblies fitting closely within the safety sleeve 46, as shown in Figure 1, and these sealing assemblies 20 together with the rotatable packing assembly 25 in the tubing head perform the function of the conventional separate blow out preventer thus preventing blow outs and enabling the operator to continue drilling operations in the presence 30 of high well pressure. More than one of the drill stem sections may be equipped with these sealing assemblies so arranged that a seal will at all times be maintained between the drill stem and the safety sleeve 46 when the drill stem is 35 elevated to break out the grief joint in the process of adding another section to the drill stem as the well is dispensed.

40 On opposite sides of the lower section 6 of the tubing head are secured the cylinders 57, 57 and connected into the outer ends of them are the pressure lines 58, 58 which lead to a pressure pump 59, as shown in Figure 3.

45 Within the cylinders 57 are the plungers 60, 60 and attached to these plungers are the plunger rods 61, 61 whose inner ends work through aligned bearings in a head section 6, as shown in Figure 4. Surrounding the plunger rods 61 and interposed between the plungers 60 and the inner ends of the cylinders 57 are the coil springs 62 which 50 normally hold the rods retracted during drilling operations. In case of high pressure in the well a fluid may be forced by the pump 59 into the cylinders 57 thus forcing the plunger and plunger rods inwardly so that in case the drill stem is 55 forced upwardly by the well pressure the upper end of the cage 48 will engage said rods 61 to prevent the drill stem from being blown out of the well.

60 The drawings and description are illustrative merely while the broad principle of the invention will be defined by the appended claims.

What I claim is:

65 1. Well drilling apparatus comprising, a tubular well head, a tubular drill stem through the head including a grief joint and having a side inlet passageway for drilling fluid, a rotatable packing assembly in the head around the grief joint of the stem and above the inlet passageway, a tubular, rotatable, sleeve depending from the head around and spaced from the drill stem, a seal between said sleeve and stem beneath said inlet passageway, an upper inlet pipe entering the head beneath said packing assembly and above said seal and a lower outflow line leading out from the space outside of said sleeve

and an annular seal between the sleeve and head above said outflow line.

2. Well drilling apparatus comprising, a tubular well head, a tubular drill stem through the head having a side inlet passageway for drilling fluid, a rotatable packing assembly in the head around the grief joint of the stem and above the inlet passageway, a rotatable, annular hanger in the head, a sleeve depending from the hanger around and spaced from the drill stem, a seal between said sleeve and stem beneath said inlet passageway, an inlet pipe entering the head beneath said packing assembly and above said seal, an outflow line leading out from the space outside of said sleeve and an annular seal between said sleeve and head above the outflow line.

3. Well drilling apparatus comprising, a tubular well head, a tubular drill stem through the head having a side inlet passageway for drilling fluid, a rotatable packing assembly in the head around the grief joint of the stem above the inlet passageway, a rotatable hanger mounted in the head and concentric therewith, a rotatable sleeve depending from, and concentric with the hanger and surrounding and spaced from the drill stem, a seal on the hanger between the head and the sleeve, a seal on the stem between said sleeve and the stem beneath said inlet passageway, an inlet pipe entering the head beneath said packing assembly and above the hanger through which fluid may enter the stem, an outflow line leading out from the space outside of the sleeve and beneath the hanger seal through which fluid may flow from the well.

4. In well drilling apparatus, a tubular well head, a tubular drill stem through the head and having a side inlet passageway for drilling fluid, a rotatable packing assembly within the head

around the stem and forming a seal around the stem above said passageway, an annular hanger rotatably mounted within the head and concentric therewith, a sleeve connected to and depending from the hanger and surrounding the drill stem and concentric therewith said sleeve being spaced from the drill stem and also spaced from the wall of the well, an annular seal ring secured to the hanger and surrounding said sleeve and forming a seal between the head and sleeve, an annular seal carried by the drill stem beneath said side inlet passageway and forming a seal between the drill stem and sleeve, an inlet pipe entering the head above said side inlet passageway and beneath the packing assembly whereby drilling fluid may be forced into the head and through said passageway and downwardly through the stem, an outflow line connected into the head beneath the hanger through which the drilling fluid returned up on the outside of the sleeve may be conducted from the head.
